US0D1101559S

(12) **United States Design Patent** (10) **Patent No.:** **US D1,101,559 S**
(45) **Date of Patent:** **** Nov. 11, 2025**

(54) **PACKAGE**

(71) Applicant: **BIG HEART PET, INC.**, Orrville, OH (US)

(72) Inventors: **Morgan Pearl Moak**, Cuyahoga Falls, OH (US); **Andrew Douglas Gordon**, Medina, OH (US); **Randall Burt Cotton**, Topeka, KS (US); **Aretha Turner Ashby**, Fairlawn, OH (US); **Adam Bricker**, Massillon, OH (US); **Christian Bushnell**, Akron, OH (US); **Elizabeth Jan Hogben**, Wadsworth, OH (US); **Natalie Aronson**, Walnut Creek, CA (US); **Tammy Chung**, Milpitas, CA (US); **William T. Keehn**, Perry, KS (US); **Jamie Lasser**, San Francisco, CA (US); **Michelle McCune**, Aptos, CA (US); **Zachary Parker Willard**, Akron, OH (US); **Andrew Deakin**, Oakland, CA (US); **Judy Guo**, San Francisco, CA (US); **Molly Rolig**, Sonoma, CA (US)

(73) Assignee: **BIG HEART PET, INC.**, Orrville, OH (US)

(**) Term: **15 Years**

(21) Appl. No.: **29/819,336**

(22) Filed: **Dec. 14, 2021**

Related U.S. Application Data

(62) Division of application No. 29/699,463, filed on Jul. 25, 2019, now Pat. No. Des. 954,551.

CLAIM

The ornamental design of a package, as shown and described.

DESCRIPTION

FIG. 1 is a front perspective view of a package according to a first embodiment showing our new design.

FIG. 2 is another front perspective view of the package shown in FIG. 1.

FIG. 3 is a front view of the package shown in FIG. 1.

FIG. 4 is a rear view of the package shown in FIG. 1.

FIG. 5 is a left side view of the package shown in FIG. 1.

FIG. 6 is a right side view of the package shown in FIG. 1.
FIG. 7 is a top view of the package shown in FIG. 1.
FIG. 8 is a bottom view of the package shown in FIG. 1.
FIG. 9 is a front perspective view of the package shown in FIG. 1 in a state of use.
FIG. 10 is a rear perspective view of the package shown in FIG. 1 in a state of use.
FIG. 11 is a front perspective view of the package according to a second embodiment.
FIG. 12 is another front perspective view of the package shown in FIG. 11.
FIG. 13 is a front view of the package shown in FIG. 11.
FIG. 14 is a rear view of the package shown in FIG. 11.
FIG. 15 is a left side view of the package shown in FIG. 11.
FIG. 16 is a right side view of the package shown in FIG. 11.
FIG. 17 is a top view of the package shown in FIG. 11.
FIG. 18 is a bottom view of the package shown in FIG. 11.
FIG. 19 is a front perspective view of the package shown in FIG. 11 in a state of use.
FIG. 20 is a rear perspective view of the package shown in FIG. 11 in a state of use.
FIG. 21 is a front perspective view of the package according to a third embodiment.
FIG. 22 is another front perspective view of the package shown in FIG. 21.
FIG. 23 is a front view of the package shown in FIG. 21.
FIG. 24 is a rear view of the package shown in FIG. 21.
FIG. 25 is a left side view of the package shown in FIG. 21.
FIG. 26 is a right side view of the package shown in FIG. 21.
FIG. 27 is a top view of the package shown in FIG. 21.

FIG. 28 is a bottom view of the package shown in FIG. 21.
FIG. 29 is a front perspective view of the package shown in FIG. 21 in a state of use.
FIG. 30 is a rear perspective view of the package shown in FIG. 21 in a state of use.
FIG. 31 is a front view of the package shown in FIG. 21 in a state of use.
FIG. 32 is a front perspective view of the package according to a fourth embodiment.
FIG. 33 is another front perspective view of the package shown in FIG. 32.
FIG. 34 is a front view of the package shown in FIG. 32.
FIG. 35 is a rear view of the package shown in FIG. 32.
FIG. 36 is a left side view of the package shown in FIG. 32.
FIG. 37 is a right side view of the package shown in FIG. 32.
FIG. 38 is a top view of the package shown in FIG. 32.
FIG. 39 is a bottom view of the package shown in FIG. 32.
FIG. 40 is a front perspective view of the package shown in FIG. 32 in a state of use.
FIG. 41 is a rear perspective view of the package shown in FIG. 32 in a state of use.
FIG. 42 is a front view of the package shown in FIG. 32 in a state of use.
The broken lines in FIGS. 9, 10, 19, 20, 29-31, and 40-42 in the form of two pet chews depict environmental subject matter and form no part of the claimed design. The remaining broken lines in the drawings depict portions of the package that form no part of the claimed design.
